HEADER

John E. Loeffler, Houston, Tex., assignor to
 Thornhill-Craver Company, Houston, Tex., a
 corporation of Texas

Application October 23, 1946, Serial No. 705,081

7 Claims. (Cl. 138—95)

1

This invention relates to headers or return bend fittings and refers more particularly to the seats and plugs used in conjunction with plug type fittings of this character.

In furnace work of the type utilizing a continuous tubular passage surrounding a heating chamber, return bend fittings are employed to connect the ends of adjacent tubes. It is often desirable to roll the tube ends into the tube receiving openings of the fittings. In order to facilitate the rolling in of the tube ends openings are provided in the header in axial alignment with the tube fittings. These openings also facilitate cleaning or inspection of the interior of the tubes and the removal of damaged tubes. Removable closures are provided to plug up the openings. The closure plugs must provide a seal at all times the furnace is in operation. This has presented a real problem due to the magnitude and variation of both pressure and temperatures that are encountered.

An object of this invention is to provide an improved plug type header capable of operating over wide ranges of temperatures and pressure.

Another object is to provide a plug type header having a seat for a closure plug wherein the seat retains a uniform configuration through wide variations of temperature and pressure conditions and a novel closure plug therefor.

A further object is to provide a plug type header wherein pressure within the header urges a portion of the plug between two inwardly tapered surfaces to insure seating of the plug providing a seal.

Yet another object is to provide an improved closure plug adaptable for use in conjunction with return bend fittings or the like.

Other and further objects of the invention will appear from the following description:

In the accompanying drawings which constitute a part of the instant specification and are to be considered in conjunction therewith, and wherein like reference numerals designate like parts in the various views:

Fig. 1 is an end view of a header embodying this invention wherein one of the closure plugs has been removed for clarity; and

Fig. 2 is an elevational view partially in section of the header shown in Fig. 1.

Referring to the drawings, numeral 3 designates the header body. The body may comprise a casting having two cylindrical fitting portions 4 and an adjoining or supporting bridge portion 5. The fitting portions have openings at each end. The openings 6 are machined to re-

2

ceive a tube, not shown in the drawings, which may be rolled in place. The openings 7 are axially aligned with openings 6 and provide access to the interior of the header to facilitate placement and removal of tube ends in opening 6 and also make possible the cleaning of coke, carbon or other deposits from the interior of the tubes. In addition, the openings provide for inspection of the tube interiors to determine their conditions.

The openings 7 are provided with seats 8. These seats preferably are tapered in order to sealingly receive a closure plug 9. The portion of the body wall which surrounds and supports seat 8 is of uniform thickness. This is accomplished by spacing the seat above the bridge portion 5 of the header. It will be seen by reference to Fig. 2 that the portion of the header which carries the seat is boss like and that the portions 20 of the seat and boss included in any plane passed through the seat normal to the seat axis are of uniform circumferential thickness. Thus, expansion or contraction of the body wall surrounding the seat due to temperature and pressure 25 changes will be uniform and the seat will retain its predetermined configuration.

It is to be understood that any suitable type plug may be used in conjunction with the header of this invention but that the novel plug illustrated herein is preferred and provides a simple plug unit which is best adapted for this purpose. The plug comprises the seating portion 9, locking portion 10 and an intermediate or floating portion 11. The seating portion has a seating surface adapted to fit seat 8 and an upstanding stem portion 12. It is to be understood that where desired the plug 9 may have attached thereto the customary and conventional stream line guides for directing the fluid entering the header through opening 6 into the passageway 40 through the bridge portion 5 of the header. As these guides are conventional, this has been omitted from the drawings in the interest of simplicity.

An annular member 10 constitutes the locking portion of the plug. Member 10 has formed thereon radial lugs 13 having inclined upper surfaces 13a. These surfaces 13a engage corresponding but oppositely inclined surfaces on internal 50 radial lugs 14 adjacent the opening 7 of the header to provide a bayonet type locking means. Spaces are provided between lugs 13 of the plug member 10 and lugs 14 of the header. These spaces permit mating of lugs 13 and 14 to facilitate insertion and withdrawal of the plug in open-

ing 7 when the header is to be assembled or dismantled.

Member 10 carries an apertured arm 15 and the header has an apertured protrusion or ear 16. Bolt 17 is then provided to rotate member 10 to effect a locking engagement of lugs 13 and 14. This is often referred to as a "Unibolt" coupling.

Locking member 10 does not have a direct engagement with seating portion 9 of the plug. Direct engagement between the parts is objectionable as rotation of member 10 affects the angular position of seating element 9 in seat 8 and sometimes results in an imperfect seal. The floating element 11 is provided to transmit the axial thrust for sealing the element 9.

Element 11 has a swivel connection with member 10. A portion of reduced diameter of element 11 extends within the enlarged bore of member 10. Confronting grooves are provided in member 10 and element 11 to receive a split ring 18. The ring 18 has a loose fit in the grooves to provide for relative rotation between the element and member. The diameter of the groove in member 10 is large enough to accommodate expansion of ring 18 on assembly of the unit. The floating element preferably has a tapered connection with the seating plug 9.

The tapered connection between plug 9 and floating member 11 is especially desirable in installations wherein high pressures are likely to be encountered. The angle of inclination of the angular taper of member 11 differs from that of seat 8 and is such as to provide an annular space with tapered sides. As member 11 is firmly held against upward axial displacement by locking member 10, the portion of plug 9 fitting between the tapered surfaces is wedged in place. When plug 9 is forced slightly upwardly by pressure increases within the header the seating surface of the plug is held in engagement with surface 8 and the seal therebetween is not disturbed. This is accomplished by the tapered surface on the floating member for it resists displacement of the seating surface of plug 9 from surface 8.

It is important to note that the lower end of member 10 engages a shoulder on element 11 adjacent its tapered surface whereby the seating pressure is not transmitted through ring 18. Ring 18 serves only to prevent accidental displacement of the floating element and locking member when disassembled and to facilitate removal of the plug as a unit from opening 7.

It is believed that the operation and assembly of the apparatus of this invention is obvious from the foregoing description. The header is of more or less conventional construction except for the position of seat 8 such that the seat retains a predetermined configuration regardless of expansion or contraction of the header body and seat due to pressure and temperature changes. This is accomplished by providing the seat on a boss like portion of the header body and spaced above the bridge portion.

The closure plug is a three part unit wherein member 9 serves as the seating element, element 11 provides a swivel connection between the seating element and the locking means 10 and the member 10 may be locked in place in opening 7 on rotation. This rotation engages lugs 13 and 14 due to the inclination of the engaging portions of these lugs and thus rotation of member 10 affects axial movement of the locking means, floating element and plug element. The bolt 17, acting through the apertures of arm 15 and ear

16, facilitates locking of the plug in place. The ring 18 between member 10 and element 11 provides a swivel connection therebetween.

In operation the plug unit is removed from opening 7, a tubing end is placed within opening 6 and rolled therein to provide a seal in the customary manner. When the header has been secured to adjacent tube ends the plugs may be inserted in opening 7 and locked in place by rotation of member 10. On servicing the furnace, or other unit with which the header is associated, the plug unit may be readily removed by removing bolt 17 and if necessary, tapping arm 15 to rotate member 10 in a counter clockwise direction as viewed in Fig. 1. The shock or jar is not transmitted directly to the seating plug 9 so as to score or injure the seating surfaces of either the plug or the seat 8. After inspection, cleaning or replacement of the tubes the plug units may be readily replaced.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof it is to be understood that all matter herein set forth or shown in the accompanying drawings is to be interpreted as illustrative and not in a limiting sense.

Having described my invention, I claim:

1. In a plug type header or return bend fitting, an opening in the header wall, a seat in the opening for receiving a closure plug, the seat and surrounding supporting wall having a uniform thickness whereby the seat retains a predetermined configuration under application of pressure by the plug and regardless of temperature changes.

2. In a plug type header or return bend fitting including a body with spaced apart fitting portions, a supporting bridge therebetween, and a passageway establishing communication between the portions, an opening in one of the portions and a seat disposed in the opening, said seat and surrounding body wall having a uniform thickness upon all planes passing through the seat and normal to the seat axis, whereby the seat retains a predetermined configuration regardless of temperature variations.

3. In a plug type header adaptable for use as a return bend fitting for tubes or the like, including a body having spaced apart tube receiving portions with a supporting bridge therebetween and a passage communicating between said portions, an opening in one of said portions, and a seat disposed therein, said seat adapted to receive a closure plug, said seat and adjacent portion of the wall having a uniform thickness reducing the likelihood of distortion of the seat from a predetermined configuration in response to application of pressure by the closure plug or in response to temperature variations.

4. A plug type header or return bend fitting for establishing communication between the ends of adjacent tubes comprising a body having spaced fitting portions, a supporting bridge section therebetween and a continuous passage communicating between the fitting portions, a boss on the body having an opening therein com-

municating with the continuous passage a seat in the boss spaced from the main portion of the body and adapted to receive a closure plug, said boss being spaced from the supporting bridge so that the boss and bridge do not reside in common planes whereby the boss and wall surrounding the seat may be of uniform thickness on any plane normal to the seat axis and included in the seat.

5. In a high pressure member having an opening and a plug therefor, a seat in the opening with an outwardly tapered seating surface, a removable locking assembly to secure the plug in the opening upon the seat, said locking assembly including an annular member engageable with the plug to urge the plug into sealing engagement with the seat, said annular member having an upwardly directed flat shoulder, a locking member having its lower end surface complementary to the surface of the flat shoulder of the annular member and engageable with said flat shoulder of the annular member to urge the same into contact with the plug, and a loose swivel connection between the annular member and locking member permitting rotative and limited lateral movement of the locking member relative to the annular member and plug.

6. In a plug type header or return bend fitting wherein an opening is provided in the header wall, an annular seat within the opening, a closure plug element adapted to engage the seat and having an axial stem extending outwardly through the opening, an annular follower member surrounding the stem and engageable with the upper surface of the plug element, said follower member having an external annular flat shoulder nearer its lower portion, an annular locking member surrounding the upper portion of the follower member and having its lower end surface complementary to the surface of the flat shoulder of the follower member engageable with the flat shoulder of said follower member

to urge the same into contact with the plug, and a loose swivel connection between the locking member and the follower member which permits rotative as well as limited lateral movement of the locking member with respect to the follower member.

7. In a plug type header or return bend fitting wherein an opening is provided in the header wall, an annular seat within the opening, a closure plug element adapted to engage the seat and having an axial stem extending outwardly through the opening, an annular follower member surrounding the stem and engageable with the upper surface of the plug element, an annular locking member surrounding the upper portion of the follower member and engageable with said follower member to urge the same into contact with the plug, and a loose swivel connection between the locking member and the follower member which permits rotative as well as limited lateral movement of the locking member with respect to the follower member, the annular seat and surrounding supporting wall having a uniform thickness whereby said seat retains a predetermined configuration under application of pressure by the plug element and regardless of temperature changes.

JOHN E. LOEFFLER.
